UNITED STATES PATENT OFFICE.

GEORGE O. OLSEN, OF BOSTON, MASSACHUSETTS, ASSIGNOR, BY MESNE ASSIGNMENTS, TO THE MANUFACTURING ENGINEERS INC., OF BROOKLINE, MASSACHUSETTS, A CORPORATION OF MASSACHUSETTS.

FUEL HEATER.

1,413,607.

Specification of Letters Patent. Patented Apr. 25, 1922.

Application filed March 19, 1917. Serial No. 155,701.

To all whom it may concern:

Be it known that I, GEORGE O. OLSEN, a citizen of the United States, residing at Mattapan, Boston, in the county of Suffolk 5 and State of Massachusetts, have invented new and useful Improvements in Fuel Heaters, of which the following is a specification.

This invention relates to improvements 10 in charge forming devices for internal combustion engines.

The object of the invention is to provide a simple device adapted to preheat the elements which unite to form a charge and 15 after the mixing of said elements to subject the charge to heating instrumentalities before it is admitted to the combustion engine and is an improvement over my co-pending application Serial No. 119,839, 20 filed September 13, 1916.

The invention consists in the combination and arrangement of parts set forth in the following specification and particularly pointed out in the claims.

25 Referring to the drawings:

Figure 1 is a plan view of a device embodying my invention and

Fig. 2 is a side elevation, partly in section, of said device with a carbureter shown 30 connected therewith.

Like numerals refer to like parts in both views of the drawings.

In the drawings, 1 is a conductor for the heating medium which, in the present case, 35 is the exhaust from the engine to which the device is attached. Formed intermediate the ends of said conductor 1 is an enlarged portion 2. A second conductor 3 extends through the enlargement 2 in a direction 40 substantially at right angles to the conductor 1. One end of the conductor 3 is provided with means preferably consisting of screw threads 4 for connecting said conductor with the internal combustion engine.

45 The opposite end of said conductor 3 communicates directly with a carbureter 5 secured to the bottom of the enlargement.

The enlarged portion 2 of the conductor 1 provides ample space around the conductor 50 3 for the products which exhaust from the engine to pass directly therethrough without being retarded, although they are deflected around the conductor 3.

The portions of the conductor 1 that are

separated by the enlargement 2 project laterally in opposite directions from said enlargement at 6 and 7. These sections are preferably cylindrical in form, terminating in screw threaded ends 8 which may be attached to the exhaust pipe of the engine. 55

Mounted upon the portion 6 of said conductor is a casing 9 substantially cylindrical in form and bored at 10 to receive and fit the portion 6. A hub 11, formed at one end of said casing 9, is provided with a set 60 screw 12 which engages the periphery of the cylindrical portion 6 of the conductor 1 and secures the casing 9 thereto.

The casing 9 has a series of apertures 14, arranged preferably at one end, through 70 which air may be admitted to said casing into contact with the outer surface of the portion 6 of the conductor 1. The casing 9 also has a discharge orifice 15 having connection, through a pipe 16, with the air inlet of the carbureter 5. The opposite end 17 of the casing 9 is preferably closed, admitting no air into the casing 9 from that end. 75

Surrounding the cylindrical portion 7 of 80 the conductor 1 is another casing 18 similar in construction to the casing 9 and constituting a fuel receptacle. This casing is provided with an inner cylindrical wall 19 which fits the outer periphery of the section 7 so as to absorb heat from the interior of the conductor 1.

An annular chamber 20 within the casing 18 communicates with the fuel inlet port 21 of the carbureter 5 preferably through a 90 fuel pipe 22 connected with said casing 18 in the outer wall thereof at 23. Fuel is supplied to the chamber 20 through an inlet port 24 connected by means of a pipe 25 to the fuel reservoir, not shown in the drawings. 95

The operation of the device hereinbefore specifically described is as follows:

Assuming that the inlet end, indicated by the arrow *a*, of the conductor 1, is connected with the exhaust pipe of an internal combustion engine and the screw threaded portion 4 of the conductor 3 to the inlet port of said engine, air will be drawn by the suction within the cylinders of the engine in 105 the usual manner through the air inlets 14 of the casing 9 and pipe 16 to the mixing chamber 26 of the carbureter. Simultane-

ously with the sucking in of the air, fuel will be drawn, in like manner, through the chamber 20, pipe 22, and inlet port 21 of the carbureter to the mixing chamber 26 and mixed in proper proportions with the air. The mixture will then be sucked by the engine through the conductor 3 into the explosion chamber of said engine.

As said air and fuel pass through their respective casings they will contact with the heated walls thereof and absorb heat from the conductor 1 heated by exhaust gases from the engine. The preheating of the fuel greatly assists the vaporizing thereof within the mixing chamber of the carbureter and the preheating of the air effects a more perfect mixture of the vaporized fuel with said air in the carbureter.

After being mixed the charge passes from the carbureter through the conductor 3 and is again heated at this point before entering the engine, said conductor 3 being heated by the products of combustion as they pass through the conductor 1, consequently when the heated charge enters the combustion chamber it will be in a more perfect condition to be fired than is usually the case in internal combustion engines and practically all of the carbon will be consumed instead of being deposited upon the inner walls, ports and valves of the combustion chamber.

Furthermore, owing to this preheating of the elements which compose the charge, before they are mixed and of the mixture, prior to its being admitted to the engine, kerosene and other low grades of oil may be utilized as fuel, and all danger of carbonizing the engine will be practically eliminated.

The portions of the conductor 1 that are separated by the enlargement 2 are identical in size and shape and the air casing 9 and fuel receptacle 18 are interchangeable thereon. Furthermore said casings may each be rotated upon the conductor 1 to locate the discharge orifice 15 of the air casing and the inlet and discharge ports of the fuel receptacle to meet varying piping conditions found in different types of engines.

Having thus specifically described my invention what I claim and desire by Letters Patent to secure is:

1. A device of the class described having, in combination, an exhaust tube, having a central enlarged portion integral therewith, a casing, detachably mounted upon and surrounding said exhaust tube at each side of said enlarged portion, a carbureter, means for providing communication between one of said casings and the fuel inlet of said carbureter, and means for providing communication between the other casing and the air inlet of said carbureter, each of said casings being interchangeable at each side of the enlarged portion.

2. A device of the class described having,

in combination a conductor for the heating medium, having a central enlarged portion and two oppositely disposed members integral therewith, a fuel casing rotatably mounted upon and detachably secured to said conductor, an air casing rotatably mounted upon and detachably secured to said conductor, each of said casings entirely surrounding said conductor and being interchangeable thereon, means constructed and arranged to mix the air and fuel from said casings, and means for conducting the mixture from said mixing means through said conductor.

3. A device of the class described having, in combination, a conductor for the heating medium comprising a centrally disposed enlarged portion and members integral with and extending laterally from said enlarged portion in opposite directions, a casing surrounding each of said laterally extending members adapted to respectively contain fuel and air, and also adapted to be interchangeable upon said laterally extending member, means for mixing said fuel and air, and means for conveying the mixture without opposition through said conductor, in a direction substantially at right angles to that of said medium.

4. A device of the class described having, in combination, a conductor, an enlarged portion arranged intermediate of the ends of said conductor, an air casing detachably mounted upon and surrounding said conductor adjacent to one side of said enlarged portion, a fuel casing detachably mounted upon and surrounding said conductor adjacent to the opposite side of said enlarged portion, said air casing and said fuel casing being interchangeable upon said conductor, a carbureter, means connecting said air casing and said fuel casing with said carbureter, and means for conducting a charge from said carbureter through said enlarged portion.

5. A device of the class described having, in combination, a conductor for the heating medium, including an enlarged portion formed integral with said conductor intermediate of the ends thereof, an air casing surrounding and detachably secured to said conductor adjacent to and at one side of said enlarged portion, a fuel receptacle surrounding and detachably secured to said conductor adjacent to the other side of said enlarged portion, said air casing and said fuel receptacle each being rotatable and interchangeable upon said conductor, a mixing device connected respectively with said fuel receptacle and said air casing, and a second conductor connected with said mixing device and extending transversely of said first conductor through said enlarged portion adapted to heat said mixture.

6. A device of the class described having, in combination, a cylindrical conductor pro-

vided with an enlarged portion integral therewith intermediate the ends thereof, a tube integral with and extending through said enlarged portion substantially at right angles to said cylindrical conductor, a fuel receptacle surrounding and detachably secured to said cylindrical conductor, means for securing said receptacle to said conductor, an air casing surrounding and detachably secured to said cylindrical conductor and provided with a plurality of air inlet ports, means for securing said air casing to said cylindrical conductor, said

fuel receptacle and said air casing being interchangeable upon said cylindrical conductor, a carbureter having communication with said tube, and means for connecting said fuel receptacle and said air casing with said carbureter.

In testimony whereof I have hereunto set my hand in presence of two subscribing witnesses.

GEORGE O. OLSEN.
